UNITED STATES PATENT OFFICE

2,032,317

COFFEE MAKER

Hugo Frank, Hartford, Conn., assignor to The
Silex Company, a corporation of Connecticut

Application February 5, 1935, Serial No. 5,087

25 Claims. (Cl. 53—3)

My invention relates to coffee makers.

It has among its objects to provide an improved resilient seal of the type adapted for use in connection with glass coffee makers of the vacuum type and having improved internal and external sealing structure disposable between the neck of a lower bowl and the depending stem of an upper bowl during the coffee making operation. A further object of my invention is the provision of a seal of the above type which can be more easily slipped on and off the stem while providing improved sealing engagement with the latter; and, more specifically, such a seal having an improved stepped axial passage for receiving and sealing the stem, and providing relatively thin yieldingly supported wall portions normally spaced from the stem. A still further object of my invention is the provision of a seal body of resilient material having an improved external sealing area adapted more particularly to cooperate with the constricted portion of the lower bowl neck and provide a plurality of vertically spaced bands of sealing engagement therewith, and having means for supporting the wall of the seal body in an improved yielding manner relative to the stem inside said lower sealing area whereby to avoid jamming of the seal in the neck. These and other objects and advantages of my improved seal construction will, however, hereinafter more fully appear.

In the accompanying drawing I have shown for purposes of illustration two forms which my invention may assume in practice.

In this drawing,—

Fig. 1 is an enlarged side elevation, partly in section, of a coffee maker equipped with my improved seal, the upper and lower bowls being largely broken away;

Fig. 2 is a view of the seal of Figure 1 removed from the stem, and

Fig. 3 is a view similar to Figure 2 showing a modified construction.

My invention is shown herein applied to a coffee maker comprising a lower bowl 1 having an upstanding bell-mouthed neck 2, and an upper bowl 3 having a depending, and usually tapered, stem 4 extended into the neck 2 of the lower bowl, my improved seal being disposed on the upper portion of the stem 4 adjacent the bottom of bowl 3 and, with the stem 4, disposed in the neck 2 of the lower bowl.

As in previous constructions, the seal comprises a generally tubular body 5 of resilient material such as soft, live rubber or the like having an axial passage 6 which engages and seals the stem

4. The seal also has adjacent its upper end a laterally extending flange terminating in a thin edge 7 which forms the upper limit of an external sealing area which is adapted to be received in and seal the bell-mouthed neck 2.

In accordance with the present invention, both the external sealing area of the seal body and the axial passage 6 for sealing the stem are of an improved construction and cooperate with the bowl neck and stem respectively in a new and improved manner.

Considering first the new axial passage 6, it will be noted that the same, as illustrated in Figures 1 and 2, is of substantially uniform diameter at the upper end thereof, conforming to and providing a relatively long band of sealing engagement 8 with the stem 4. Below this band, the passage is formed with receding annular stepped surfaces 9, leading to the lower extremity of the passage 6, of which two are herein shown, forming spaced annular edges 10 of increasing diameter toward the lower end of the passage. From an inspection of Figure 2, it will be evident that the annular surfaces 9 being of larger diameter than the sealing surface 8 thereabove will remain largely out of contact with the stem 4 or, if engaging the same lightly at the edges 10, will offer little resistance as the seal is worked up on the stem or subsequently removed therefrom.

Referring particularly to the external surface 30 of the seal, as shown in Figures 1 and 2, it will be noted that two sealing areas are provided. One is an upper concave sealing portion 11 directly beneath the edge 7, which conforms generally to the curve of the bell-mouthed neck 2 35 and the other is a lower sealing area extending from the curved portion 11 to the lower end of the seal body. The upper sealing area 11 engages said neck 2 on the upper flared portion thereof only when a bowl is encountered of 40 slightly larger neck diameter than that illustrated in Figure 1. In a lower bowl of normal neck diameter, as illustrated in this figure, the concave sealing portion 11 is slightly spaced above the flared mouth of the neck, and the seal 45 is obtained on the lower sealing portion above mentioned at substantially the most constricted portion of the bowl neck.

As shown in Figures 1 and 2, the lower external sealing area above mentioned, which is 50 slightly tapered as shown in Fig. 2 and more abruptly tapered when the seal is in place on the tapered bowl stem 4, is provided with an annular recess, or groove, 12. The side walls of this groove being generally symmetrical and ex- 55

tending outwardly from spaced points along the bottom of the groove, form yielding spaced generally symmetrical annular sealing bands 16, 17 of slightly different diameter extending around the outer ends of these walls. Herein, it will also be noted that the walls of the groove are so spaced from one another as to prevent possible contact when flexed during use and resultant increased resistance to longitudinal movement in a bowl neck. Also, the groove herein is also of such depth as to form a relatively thin wall portion 13 yieldingly supported out of contact with the stem by the annular edges 10. Further, due to stretching of the seal required to insert the upper end of the tapered stem 4 in the passage 6 thereof, the pressure of the stem on the sealing portion 8 flexes the thin wall portion 13 so that the groove 12 has a convex outer surface 14 which, with the upper and lower annular edges 16 and 17 formed by the groove, provides three vertically spaced bands of contact with the convex throat of the neck 2. The wall portion 15 below the groove 12 is also relatively thin and is also yieldingly supported, adjacent the edge 10, out of engagement with the stem 4. It will also be noted that the internal annular edges 10 are disposed in horizontal planes within the vertical limits of the groove 12 and closely adjacent the upper and lower extremities thereof.

In the modification illustrated in Figure 3, I have shown the seal body generally indicated at 5a having an axial stem sealing passage 6a. The seal of this figure also has the external, annular flange terminating in the edge 1a constituting the upper limit for the external sealing area 11a, merging into the lower generally tapered sealing portion which in this construction is free from grooves, such as groove 12 of Figures 1 and 2.

The axial passage 6a has the lower stepped surfaces 9a forming the annular edges 10a and also has an upper band of sealing engagement 8a with the upper bowl stem, corresponding somewhat to Figures 1 and 2. In the construction illustrated in Figure 3, and also in that of Figures 1 and 2 if desired, the sealing band 8a can be much abbreviated by the formation of a deep axial recess 18 at the upper end of the seal body, leaving a relatively short sealing band 8a intermediate the ends of the seal body. Here it will be noted that the sealing band 8a, when the seal is on a bowl stem and is in position somewhat above the point of maximum constriction of the lower bowl neck, thus leaving the relatively thin yieldingly supported wall portions 15a and 13a, which enter the throat portions, free to yield readily as in the previously described Figures 1 and 2.

In the use of my improvement, the stem is first inserted in the passage 6 of the seal, and the seal is worked well up onto the stem to a point adjacent the bowl 3 using a combined axial and rotary motion. During this operation, the seal is considerably expanded causing the internal sealing portion 8 to hug the stem and effect a good seal. The edges 10 at the lower end of the seal engage the stem, due to the fact that the tapered stem at this point is larger in diameter than the lower stepped surface 9. As will be evident from Figure 1, the stepped surfaces 9, however, except at their edges 10, are spaced laterally from the stem; thus supporting the thin flexible wall portions 15 and 13 yield-

ingly out of contact with the stem by the contact of the edges 10.

The upper bowl stem with the seal thereon is next inserted in the lower bowl, the seal being given a slight twisting motion in the lower bowl neck, if necessary, by rotation of the upper bowl to effect an air tight seal with the neck, although with my improved seal such rotation is usually not required. With a neck such as shown in Figure 1, the lower annular sealing edge 16, formed by groove 12, will easily pass through the constricted portion of the bowl neck, due to the yielding nature of the thin wall portion 15, permitting the upper sealing edge 17 of said groove to engage said neck at some point slightly above the most constricted portion thereof, it being noted that the upper sealing edge 17, being located on a relatively thick wall portion of the seal body 5 which is in firm engagement with the stem, will yield less readily than the yieldingly supported lower edge 16 above mentioned. Accordingly, two vertically spaced bands of sealing engagement with the bowl neck 2 are provided by the edges 16 and 17. Further, it will be noted that due to the shape of the wall portion 13, a third sealing band is provided intermediate the edges 16 and 17 at the crown of the convex surface 14.

It will thus be evident that I have provided a seal which can be readily installed on the tapered stem of an upper coffee maker bowl and as readily removed therefrom, due to the decreased area of the axial passage which is in contact with the stem. It will also be noted that, while the lower half of the seal passage is substantially out of contact with the stem, and the wall of this lower half is relatively thin, the same is adequately supported on the stem by the annular edges 10 in such manner as to permit the lower external sealing area to yield readily. Further it will be noted that the portion 8 of the seal body which engages and provides the seal on the stem, and hence is less yieldingly supported on the stem, is located above the point of maximum constriction of the lower bowl neck, and that the lower part of the seal which is disposed in the neck portion, where jamming of the seal can occur, is so supported out of contact with the stem as effectively to yield and prevent such jamming, while also effectively sealing the neck.

Attention is also directed to the fact that the seal is particularly well adapted to cooperate with bowls having the usual wide variation in neck diameters inevitable in making blown glass receptacles. Thus in the illustrative bowl shown in Figure 1, three vertically spaced bands of sealing engagement are provided at 14, 16, and 17 without requiring a forcible entry of the seal into the restricted portion of the neck, due to the yielding support of the wall portions 13 and 15 above described. It will be evident, however, that the same seal can be accommodated in bowls having considerably smaller and larger neck diameters while still enabling the seal at one or more of the three points to be obtained. This is due in part to the ability of the inherently resilient and yieldingly supported wall portions 15 and 13 to expand into engagement with the lower bowl neck while the same are free to be compressed inwardly when inserted in a neck of small diameter, and also to the provision of the sealing bands 16 and 17, herein of different diameter. Attention is also directed to the structure and arrangement of these sealing bands 16 and 17 which enables them to seal effectively, selectively or together, in bowl 75

necks of different diameter irrespective of the form of axial stem aperture provided in the seal. Further, the spacing of the walls thereof herein is such as to prevent the increased or built up resistance to longitudinal movement of the seal arising from contact of the walls with each other experienced in prior grooved seals. It will further be noted that in the illustrative structure, the use of a generally symmetrical groove enables generally symmetrical sealing bands 16 and 17 of different diameter to be formed which present vertically spaced yieldable bands adapted effectively to engage and seal bowl necks of different diameter despite the fact that both of these bands are on wall portions of the groove which project outward at spaced points from the bottom of the latter. These and other advantages of my improved construction will, however, be clearly apparent to those skilled in the art.

20 While I have in this application specifically described two forms which my invention may assume in practice, it will be understood that these forms of the same are shown for purposes of illustration and that the invention may be modified 25 and embodied in various other forms without departing from its spirit or the scope of the appended claims.

What I claim as new and desire to secure by Letters Patent is:—

- 30 1. A seal for coffee makers or the like comprising a seal body of yieldable material having an external sealing area receivable in a lower bowl neck and having an axial passage adapted to receive and seal an upper bowl stem, said passage having a sealing portion and having a lower portion of increasing diameter extending to the lower end of said passage.
- 40 2. A seal for coffee makers or the like comprising a seal body of yieldable material having an external sealing area receivable in a lower bowl neck and having an axial passage adapted to receive and seal an upper bowl stem, said passage having a portion conforming to and sealing said stem and having an enlarged stepped axial recess below said sealing portion extending to the lower end of said passage.
- 50 3. A seal for coffee makers or the like comprising a seal body of yieldable material having an external sealing area receivable in a lower bowl neck and having an axial passage adapted to receive and seal an upper bowl stem, said passage having a portion conforming to and sealing said stem and having below said sealing portion an axial recess of increased diameter at the lower end of said passage having a stepped surface providing a plurality of annular edges between said stem sealing portion and the lower end of said seal.
- 60 4. A seal for coffee makers or the like comprising a seal body of yieldable material having an axial passage adapted to receive and seal an upper bowl stem, the lower end of said passage having an enlarged diameter providing a deep axial stepped recess at the lower end of said seal body and having a more constricted portion thereabove adapted to engage and seal with a bowl stem.
- 70 5. A seal for coffee makers or the like comprising a seal body of yieldable material having upper and lower external sealing surfaces and having an axial passage adapted to receive and seal an upper bowl stem, said passage having an upper sealing portion inside said upper external sealing portion and an enlarged axial recess of increasing diameter extending to the lower end of
- 80 said passage inside said lower external sealing portion.
- 90 6. A seal for coffee makers or the like comprising a seal body of yieldable material insertable in a bowl neck and having an axial passage adapted to receive and seal an upper bowl stem, the wall of said passage having an upper stem sealing portion and a lower portion comprising an enlarged axial recess of increasing diameter and of maximum diameter at its lower end providing a relatively thin flexible wall for said seal body engageable with a stem when said seal body is inserted in a bowl neck.
- 100 7. A seal for coffee makers or the like comprising a sealing portion of yieldable material having an axial passage and having an external sealing area receivable in a lower bowl neck, said sealing area having an annular groove intermediate its extremities of such width as to space the wall's of said groove out of possible contact when flexed and having spaced contact bands around the edges of said groove.
- 110 8. A seal for coffee makers or the like comprising a sealing portion of yieldable material having an axial passage and having an external sealing area receivable in a lower bowl neck, said sealing area having an annular groove intermediate its extremities provided with walls extending outwardly from spaced points along the bottom of said groove and the edges of said groove forming spaced contact bands at the outer ends of said walls.
- 120 9. A seal for coffee makers or the like comprising a sealing portion of yieldable material having an axial passage and having an external sealing area receivable in a lower bowl neck, said sealing area having a generally symmetrical groove intermediate its extremities providing generally symmetrical spaced annular sealing edges and having generally symmetrical outwardly extending wall portions carrying said sealing edges.
- 130 10. A seal for coffee makers or the like comprising a sealing portion of yieldable material having an axial passage and having an external sealing area receivable in a lower bowl neck, said sealing area having spaced annular sealing edge portions carried on adjacent outwardly extending walls substantially spaced out of possible contact with one another along the length of said area, and a surface portion of reduced diameter intermediate said edge portions and connecting said adjacent walls.
- 140 11. A seal for coffee makers or the like comprising a seal body of yieldable material having an axial sealing passage and an enlarged recess below the same and also having an external sealing area receivable in a lower bowl neck, said sealing area having a single enlarged groove therein positioned opposite the upper end of said recess.
- 150 12. A seal for coffee makers or the like comprising a seal body of yieldable material having an axial sealing passage and having an external sealing area receivable in a lower bowl neck, said sealing area having an annular groove intermediate its extremities providing spaced contact bands at the edges of said groove and upon flexure of said groove an intermediate contact band between said edges.
- 160 13. A seal for coffee makers or the like comprising a seal body of yieldable material having an axial sealing passage and having an external sealing area receivable in a lower bowl neck, said external sealing area having spaced contact bands and a reduced portion therebe-

tween and said sealing passage having means for enabling flexure of said intermediate portion.

14. A seal for coffee makers or the like comprising a seal body of yieldable material having an axial sealing passage and having an external sealing area receivable in a bowl neck, said sealing area having spaced annular sealing edges and said axial passage having a communicating enlarged recess enabling flexure of said sealing area to present an intermediate sealing band between said sealing edges.

15. A seal for coffee makers or the like comprising a seal body of yieldable material having an axial sealing passage and having an external sealing area receivable in a bowl neck, said sealing area having spaced annular sealing edges and said axial passage having an enlarged recess below the same having a step below one sealing edge and above the other.

16. A seal for coffee makers or the like comprising a seal body of yieldable material having an axial sealing passage and having an external sealing area receivable in a bowl neck, said sealing area having spaced annular sealing edges and said axial passage having an enlarged recess below the same having a step below one sealing edge and above the other and a further enlarged recess below said step.

17. A seal for coffee makers or the like comprising a seal body of yieldable material having an external sealing area receivable in a lower bowl neck and having an axial passage adapted to receive and seal an upper bowl stem, said passage having a stem sealing portion adjacent the top of said seal and an enlarged axial recess at the bottom of the seal providing a lower thin flexible wall portion, and said external sealing area having a single enlarged annular groove in said wall portion opposite the upper part of said recess.

18. A seal for coffee makers or the like comprising a seal body of yieldable material having an external sealing area receivable in a lower bowl neck and having an axial passage adapted to receive and seal an upper bowl stem, the wall of said passage having an upper stem sealing portion and having a lower axially recessed portion providing receding stepped surfaces forming vertically spaced annular edges, and said external sealing area having an annular groove in the vicinity of said sealing edges.

19. A seal for coffee makers or the like comprising a seal body of yieldable material having an external sealing surface and having an axial passage adapted to receive and seal an upper bowl stem, the wall of said passage having an intermediate stem sealing portion and having upper and lower axial recesses of increased diameter and respectively having walls of increasing and decreasing thickness.

20. A seal for coffee makers or the like comprising a seal body of yieldable material having an external sealing surface and having an axial passage adapted to receive and seal an upper

bowl stem, the wall of said passage having an intermediate stem sealing portion and having upper and lower axial recesses of increased diameter, one of said recesses having annular stepped surfaces providing a plurality of annular edges.

21. In a vacuum type coffee maker, an upper bowl having a stem, and a seal of yieldable material having an axial passage adapted to receive and seal said stem, said passage having an upper band of sealing engagement with said stem and having a lower axially recessed portion of increasing diameter extending to the lower end of said passage and providing a yieldingly supported wall portion of reduced thickness laterally spaced from said stem.

22. In a vacuum type coffee maker, an upper bowl having a depending stem, and a seal of yieldable material having an axial passage adapted to receive and seal said stem, said passage having an upper band of sealing engagement with said stem and having a lower enlarged axial recess extending to the end of said passage having a stepped surface providing a plurality of annular edges between said sealing band and the lower end of the seal.

23. In a vacuum type coffee maker, an upper bowl having a depending stem, and a seal of yieldable material having an axial passage of smaller diameter than said stem adapted to receive and seal said stem, the wall of said passage having an upper stem sealing portion and a lower stepped portion forming vertically spaced annular edges engaging said stem.

24. In a vacuum type coffee maker, an upper bowl having a depending stem, and a seal of yieldable material having an axial passage adapted to receive and seal said stem, said seal having a relatively thick upper wall portion providing a sealing band of engagement with said stem and having its axial passage recessed at the lower end of the seal to provide a wall portion of decreasing thickness extending to the lower end of said seal and having supporting engagement with said stem at vertically spaced points, the portions of said wall between said vertically spaced supports being spaced from said stem.

25. In a vacuum type coffee maker, a lower bowl including an upstanding neck having a throat portion terminating in a bell mouth, an upper bowl having a depending stem receivable in the neck of said lower bowl, and a seal of resilient material having an axial passage receiving and sealing said stem and also having an external sealing portion receivable in said neck, said seal having a lower wall portion of reduced thickness yieldingly supported out of contact with said stem and having an external annular groove in said yieldingly supported wall portion forming a plurality of vertically spaced narrow annular bands of sealing engagement with said lower bowl neck.

HUGO FRANK.
